UNITED STATES PATENT OFFICE.

HALVER R. STRAIGHT, OF ADEL, IOWA.

TUNNEL KILN.

Application filed July 6, 1920. Serial No. 394,344.

To all whom it may concern:

Be it known that I, HALVER R. STRAIGHT, a citizen of the United States, residing at Adel, county of Dallas, State of Iowa, have 5 invented an Improved Tunnel Kiln, of which the following is the specification.

This invention relates to what is known as tunnel or continuous kilns for burning hollow building blocks or drain tile.

There have been quite a number of 10 these kilns constructed, and operated for burning china ware and such small articles, but so far as I am aware no kilns of this type have been successfully constructed for rapidly and efficiently burning brick or 15 hollow building blocks and drain tile.

There is a very large amount of material 20 used in articles of this kind and requires a very large number of heat units to burn them, which must be very rapidly and uniformly imparted to the ware without cracking or warping it. Even more care must be 25 taken in the cooling of the ware, which also to be efficient in operation must be very rapidly done.

In ware of this kind the temperature may 30 be very rapidly increased, or decreased without injury to said ware if the temperature is evenly and uniformly increased or decreased.

The object of my invention is to provide 35 a tunnel or continuous kiln for burning hollow building blocks or drain tile, etc., of simple, durable, and comparatively inexpensive construction, and to provide in such a structure, improved means for controlling the drafts for pre-heating, burning, and cooling, so that the ware may be moved 40 through the kiln in a comparatively short time without cracking or warping it.

A further object is to provide new and improved means whereby expansion and contraction may take place due to the heat from the furnaces, without destroying the 45 main wall construction of the arch or tunnel portion of the kiln.

A further object is to provide in a tunnel kiln having a train of cars operated intermittently, improved method of entry, and 50 exit for the cars to said kiln.

A still further object is to provide in a tunnel kiln having a train of ware bearing cars, improved floor for said cars whereby the cooling and heating may be more efficiently carried on within the kiln.

A further object is to provide in a continuous kiln means whereby a series of cars may be advanced freely through said kiln, and be subjected to a series of controllable temperatures, or zones, each of which may 60 be more or less independently regulated, without transverse partitions separating said zones, within the kiln.

These and other objects will be apparent to those skilled in the art which need not be 65 mentioned in detail.

Referring to the accompanying drawings, Fig. 1 is a plan view of my improved kiln, and

Fig. 2 is a side elevation of the same. 70

Fig. 3 is a transverse section view taken on the line 3—3 of Fig. 1.

Figure 4 is a transverse sectional view taken on the line 4—4 of Figure 1.

Fig. 5 is a transverse sectional view taken 75 on the line 5—5 of Fig. 1, through the burning zone of the kiln.

Fig. 6 is a detail longitudinal sectional view taken on the line 6—6 of Fig. 1, of the cooling end of the kiln. 80

Fig. 7 is a detail longitudinal sectional view taken on the line 7—7 Fig. 1 of the burning zone and a portion of the pre-heating zones.

Fig. 8 is a detail elevation of a portion of 85 the interior of the cooling zone, showing the draft openings.

Fig. 9 is a detail elevation of a portion of the interior of the burning zone, showing the heat conducting openings. 90

Fig. 10 is a detail sectional plan view taken on the line 10—10 of Fig. 5.

Fig. 11 is a detail sectional view taken on the line 11—11 of Fig. 1 showing the mechanism for forcing the draft to the burners. 95

Fig. 12 is a detail sectional view taken on the line 12—12 of Fig. 5 showing the draft regulating devices.

Fig. 13 is a detail sectional view showing one of the devices for imparting a positive 100 motion to the air currents.

My improved kiln comprises substantially a tunnel part 10, and furnace portion 11.

The tunnel is formed of parallel and vertical walls 12. Each wall rests on a base 105 portion 13, the inner wall of which projects inside of the inner face of the wall 12 a considerable distance. The upper edges of the walls 12 are designed to receive an arch portion 14 between them. The said walls 12 110

are held against lateral or outward movement by means of the vertical beams 15 and tie rods 16.

This arch portion 14 is constructed somewhat differently at various positions of the tunnel, as will be more fully set forth, as each section is described in detail.

Each of the inner faces of the base portions 13 are provided with a trough 17, designed to be filled with a granulated fire proof material, such as fire clay or sand.

The bottom of the tunnel is provided with tracks 18, designed to receive a train of cars 19, each of which are provided with floors 20, formed of a refractory material, such as fire brick.

The floors 20 are of such a width that their ends will terminate at a point substantially above the center of the troughs 17, and are designed to have downward projecting plates 21, designed to enter the said troughs 17, these plates are for the purpose of forming a seal, so that the lower and metallic parts of cars may be protected from the intense heat of the burners.

The floor 20 of each of the cars 19 is provided with a series of conductor members 22, formed of a refractory material. Each of said members being placed on said floor, adjacent to and transversely of each other, and provided with a longitudinal opening 23. Each member 22 has in its upper face a number of openings 24, in communication with the opening 23, for the purpose of conducting currents of air, as will be more fully set forth.

To permit cars to enter and be removed without allowing an excessive amount of cold air entering the kiln every time a car is moved into or out of the kiln, I have provided what I shall term an entry and exit vestibule, the entry vestibule being located at one end, and the exit vestibule at the opposite end of the kiln. Each of the vestibules are provided with two sliding doors, 25 and 26, spaced apart a distance equal to a little more than the length of a single car. These doors may be mounted upon any suitable hanger devices 27, having rollers 28. Each end of the tunnel is provided with an enlarged portion 29, designed to receive the doors 25 and 26, when in an opened position.

Sectional views of the cooling end of the kiln are shown in Figs. 3, 4, and 6. In Figs. 3 and 4 it will be noted that the walls 12 are comparatively thin, and the arch 14 is formed directly in said walls, near their upper ends. The space above the arch is filled with heat insulating material. Each of the base portions 13 are provided with a conduit 30, and on their upper face a series of arches of fire proof material, to form passage ways 31, in communication with the conduits 30, and of such a height as to be in line with the openings of the floor members

22. The arches being of such a width as to nearly touch the end of said floor members 22, as clearly shown in Figs. 3 and 4. The arches are shown in elevation in Fig. 8, and are of a span substantially equal to the length of a single car.

Each of the passage ways 31 are provided with a valve 32, formed of fire proof material, and designed to be operated by means of a rod 33, extending to the exterior of the kiln.

At the extreme end of the cooling end of the kiln, I have provided a sheet metal percolator having sides 34, and a top 35, the lower edge of the sides 34, rests on the top of the said arches. The sides 34 are spaced apart such a distance that a considerable space will be provided between them and the ware of the contained cars, this is to permit any blocks that might fall off of the car to lodge on top of the arches without locking the car, or scraping the remaining blocks off. The said percolator is of such a size that a considerable space 36, is left between it and the walls 12, and arch 14. This space is for the purpose of receiving cold air direct from the outside, through an air intake pipe 37. The space 36 is provided with a series of baffle plates 38, for the purpose of causing the air to circulate adjacent to the side members 34 to become warmed by radiation. The top 35 is provided with a series of openings 35^a, the number and size of which are to be determined by experiment.

The warmer end of the percolator is formed of fire-proof material, while the cooler end is formed of sheet metal, the fire-proof portion being provided to resist the high temperatures, while the sheet metal portion is provided to permit the better radiation and conduction of the heat.

Fig. 5 is a sectional view through the firing or burning zone, it will be noted that the walls 12 are somewhat thicker at this section, than at the cooling end of the tunnel.

A series of arches 39 are provided on the base wall 13, similar to those for the cooling end, except the space of each is substantially equal to the width of one of the blocks 22 of the car floor. It will be seen from Fig. 10 that the passages under the arches 39 of one side of the kiln are designed to be in line with every alternate member 22, and the passages of the arches of the opposite side in line with each intermediate member 22, this affords a very rigid short arch which will stand the intense heat to which they are exposed, also provides for a more uniform heating of the material on the cars, as the heated ends of each alternate block 22 will radiate heat to the cooler ends of the intermediate blocks.

A furnace 11 is built separate and adja-

cent to each of the walls 12 and opposite the burning zone, and comprising wall members 40, and an arch 41, one end being closed, and the opposite provided with an 5 automatic stoker device 42, Fig. 11. This stoker may be of any suitable construction and forms no particular part of my present invention. I have however provided a fan device 43 having an outlet pipe 44 leading 10 directly to the fire box of the stoker, the fan 43 is driven directly by a variable speed motor, 46, Figs. 1 and 2. The intake of the fan is in communication with the forward end of the air passage 30 as shown 15 in Fig. 11. The outer walls 40 are supported by vertical beams 47 and tie rods 48. Each of the inner walls 40 is provided with a passage way 49 opposite and in line with the passage way under the arches 39, each of 20 the passageways 49 is provided with a tube 50 formed of a refractory material, these tubes 50 are somewhat smaller than the passages 49 and are designed for a fire-proof lining and to bridge the slight space 25 between the walls 12 and 40. These tubes may be removed and replaced by new ones when burned out. They also permit a slight movement of one wall relative to the other due to expansion or contraction, etc., without 30 injury to the main tunnel walls. A new furnace may also be substituted for the old one when burned out, without having to rebuild the tunnel walls. A 35 sliding brick or block 51 is mounted adjacent to the furnace end of each of the tubes 50. Above each block 51, in the arch 41 I have provided a vertical pipe 52 having a detachable cap 53, by removing said cap a poker may be inserted in the pipe 52, and 40 the block 51 moved to position over the end of the tube 50, to form a damper for regulating the flow of air through said tubes. By removing the cap 53 the condition of the 45 fire may also be determined.

45 Adjacent to each side of the cooling zone slightly above the passage 31, I have provided a cold air pipe 54. In communication with the pipes 54, I have provided a series of lateral pipes 55 communicating with the 50 space 36. A butterfly valve 56 is provided for each of the pipes 55 and is operated by means of a handle 57. Each of the arches of the passages 31 are provided with an opening 58, a valve 59 is provided for said 55 openings and has a rod 60, by which the valve may be moved to an opened or closed position, as shown in Figs. 3 and 4.

55 Mounted above the arches 14 I have provided a passage way 61 substantially the full length of the kiln, the arch 14 is provided with a series of openings 62, having a covering brick or block 63 above each of said openings. In the cover of the passage 65 61 I have provided a pipe 64 having a detachable cap 65, by removing the cap 65 and

inserting a poker or iron rod through the pipe 64, the block 63 may be moved to one side so that the condition of material beneath may be observed. By closing the cap 65 and leaving the opening 62 partly uncovered, a portion of heated air within the kiln may be drawn off, as will again be referred to.

50 The firing zone is provided with a fire-proof lining 66, and an inclined arch 67 75 Figs. 5 and 7. These walls are so constructed that they may be easily removed without destroying the construction of the main tunnel of the kiln.

The pre-heating zone, Fig. 7 is constructed similar to the cooling zone, having 80 the same arch construction over the base portion 13, with the exception of the housing 34, which is omitted.

The intake end of the pre-heating zone, 85 or section, is provided with a vestibule similar to the one on the cooling end of the kiln.

90 For forcing air into the kiln I preferably use a low pressure blower, something like the one shown in cross section of Fig. 13, one of which is connected to the pipe 37. Each of the pipes 54 also have one end in communication with the pipe 37 as shown in Fig. 1.

95 The passage 30 has a partition 70, so that the said passage is divided into two parts, the one at the cooling end of the kiln being in communication with the fan 43, the other one in communication with the pipe 71, 100 which is in turn connected to the intake side of the blower 68^a, the cooling ends of the passages are also connected to an underground conduit 72, which is designed to lead to a drier room.

105 The passage way 61 is also connected with the conduit 72 by a pipe 73.

110 In practical operation, the cars 19 are filled with hollow building blocks, or drain tile stacked on end, so that vertical air passages are formed, and are in communication with the openings 24, in the members 22. The cars are then moved to the outer door 25 of the pre-heating end of the kiln, the door is then opened and the car moved into 115 the kiln. This is repeated until the pre-heated end of the kiln is filled with cars, the doors 25 and 26 at the opposite end of the kiln are then closed, and fires started in the furnaces, the blowers 68 and 68^a are 120 then started, the blower 68 would then cause cold air to be forced into the pipe 37, and in turn to the space 36, above the percolator 34. The valves 32 at the outer or cooler end of the kiln should be closed, thereby causing 125 the air to be forced to the forward end of the cooling zone, the forward valves however being left open so that air could be drawn through the fan casing 43 and to the furnaces 11. The heated air is then drawn 130

from said furnaces through the passages 49 and the tubes 50 to the interior of the burning chamber, thence upward and down through the ware, to be pre-heated through 5 the opening 24 of the passage 23, and to the 70 passages 31 under the arches, shown in Fig. 8, then downward through the passages 30 to the pipe 71 and out through the suction blower 68^a. The pre-heating of the material 10 may be graduated by manipulating the valves 32, so that each car may get the proper amount of heat. After the cars within the pre-heated zone have been raised to the proper temperature, new cars may be 15 added one at a time; this will cause them to enter the burning zone where they are to be stopped so that one of the floor members 22 is opposite one of the tubes 50, the hot 80 gases will enter the opening 23 as shown by arrows in Fig. 10, then upward through the hollow block and tile, then forward to the pre-heating zone and downward and outward as before described.

The cars will then be intermittently moved 25 rearward until the cooling zone is filled, the opening 23 will then be opposite the passages 31, the valves 32 should then be opened and the air allowed to enter the passage 30, the operation will then be as follows,—the 30 cold air will enter the space 36 above the metallic portion of the percolator, a certain proportion of which will flow through the openings 35^a in said housing to the vertical passageways in the stacked ware, downward 35 through the openings 24 and 23, and to the passages 30 and 31; by the proper distribution of the openings 35^a, the air may be very uniformly distributed or percolated to the ware beneath, if it is found that the ware 40 on the outer sides of the ware is cooling too fast, some of the outer openings 35^a may be closed, or vice-versa, or if it is found that the material on a car at a certain position of its movement is cooling too fast, then 45 some of the openings above said car may be closed up, or if it is cooling too slowly, some of the openings may be opened up. Regulation may also be somewhat accomplished by opening or closing the valves 32. 50 The baffle plates 38 are placed so that the air which does not enter the openings 35^a may be pulled down past the sides 34 and be heated therefore by radiation, this air will also take on heat from the arch portion 35 of the percolator, some of the air will again 55 pass through the next series of openings 35^a, but will have become slightly heated, thus as the unused portion of air advances forward past each of the baffle plates 38, 60 it will become warmer and warmer, the idea being to deliver the air to the ware at a temperature just a few degrees below the temperature of the ware, so the said ware will not become chilled and cracked from 65 unequal contraction. If it is found that

the temperature of the advancing air above the housing is raising in temperature too fast a part of the heated air may be taken off through the conduit 61 and the opening 62, this would have a tendency to reduce the 70 volume of air passing through the ware at the hot zone. Cold air may be admitted through pipes 55 from the conductor 54. It might be desirable at times to cool a certain car, say half way between the cooling 75 end and the burning zone, faster than the rest for hardening, or any other reason, the valve 56 would then be opened at the adjacent section or zone, and a comparatively large amount of cold air admitted 80 through the tube 55, or if it is desired to raise the temperature of the said section instead of lowering it, the valve 59 would be opened and the valve 56 closed, in an adjoining rear section then some of the cooler air 85 would be drawn off through the passages 31 and 30, leaving air in the said section to move slower, and cool slower, thus it will be seen that by the proper operation of the valves 32—59—56 and 63, the cooling 90 of the ware may be very rapidly, accurately, and finely graduated, so as to prevent cracking and warping, and the ware given the proper degree of hardness. The material 95 on the various parts of the cars will be uniformly treated. One advantage of this construction is that a considerable space may be left between the sides of the pile of material on the cars and the walls of the 100 housings or interior linings, and yet have a series of substantially distinct zones, each of which may be more or less independently controlled without having a transverse partition for each zone, by permitting a considerable space between the ware and wall, a block 105 accidentally falling off the pile would not lodge and stop the cars, as it would simply lay on the top of the air conducting arches.

It will also be noted that no air will 110 enter the kiln, for supplying the furnaces or otherwise, except through the pipe 37 and this is fed at a uniform volume and pressure by the blower 68. By the special arrangement of the propelling members of the 115 blowers of this type, the flow of air through the pipe 37 would not be affected by outside atmospheric conditions or the direction of a whirling and variable wind. In a similar manner the suction blower 68^a will operate to uniformly and continuously draw the 120 gases of the cooling chamber in such a manner that the currents of air will discharge gases from the kiln and deliver them to the outside atmosphere without being influenced by the action of the wind. The 125 blower 68 should be so operated that a slight pressure is applied to the cooling end, while the door 68^a should be of such dimensions and so operated that a slight vacuum is 130 created at the discharge end of the kiln.

Both of said blowers act somewhat as 5 meters, one feeding a predetermined volume of gas to the kiln, while the suction blower draws a predetermined and greater volume of gas from the kiln. The difference of volume entered by the two blowers being due to the difference in temperatures of the gases as they enter and leave the kiln.

I am well aware that means have been 10 provided for opening and closing the air passages leading to and from the kilns of this type, but none of them have provided mechanical means whereby a predetermined volume of gas may be fed to the kiln and 15 a predetermined volume taken from, without the influence of outside atmospheric conditions.

The stability of the air within the kiln is 20 maintained when the cars are taken in and out, by means of the vestibules at each end, provided with the doors 25 and 26. When it is desired to remove a car from the kiln, the door 26 is opened and the cold car moved to the vestibule, then said door 26 is closed, 25 and the door 25 opened, the car is then moved to the exterior of the kiln. The cars are moved into the kiln at the opposite end by a reverse operation; by this arrangement the kiln may be made practically air tight 30 except through the conducting passages which are under absolute control of the pressure and exhaust blower.

A conductor 72 is provided, and in communication with a drier not shown both of 35 which are exhausted by a blower similar to 68a.

The conductor 72 communicates with the 40 passage 30 at a point somewhat ahead of the fan 43, and removes a large part of air at a medium temperature, the remaining hot air is driven through the grates of the stokers by the said fans 43, the forward ends of the pipes 54 however are in communication with the intake of the fan for 45 supplying cold air, if the temperature of the air from the passage 30 is too high this cold air is controlled by a valve 75. Sometimes it is desirable to hold the ware at a given temperature in the burning process to 50 permit oxidation of the carbonaceous materials, I can accomplish this by means of the slides 57.

Thus it will be seen I have provided a 55 tunnel kiln comparatively air tight, and unaffected by outside atmospheric conditions, and in which the temperature of the various zones are under absolute control of the operator, and one in which the fuel economy is reduced to the highest degree of efficiency, 60 also in which the repairs and upkeep are reduced to a minimum.

Having thus described my invention I claim:

1. In a device of the class described, a 65 tunnel designed to receive a series of mov-

able cars, and to be divided into preheating, burning and cooling zones, and an adjacent and independently constructed furnace at each side of said burning zone, the adjacent wall of each having a series of corresponding openings, each corresponding set of which is provided with a loosely mounted refractory tube for conducting heated gases from the furnace to the said burning zone. 70

2. In a device of the class described, a 75 tunnel designed to receive a series of movable cars, and to be divided into preheating, burning and cooling zones, and an adjacent and independently constructed furnace at each side of said burning zone, the adjacent wall of each having a series of corresponding openings, each corresponding set of which is provided with a loosely mounted refractory tube for conducting heated gases from the furnace to the said burning zone, 80 a car receiving vestibule at each end of said tunnel for the purpose stated. 85

3. In a device of the class described, a 90 tunnel designed to receive a series of movable cars, and to be divided into preheating, burning and cooling zones, and an adjacent and independently constructed furnace at each side of said burning zone, the adjacent wall of each having a series of corresponding openings, each corresponding set of which is provided with a loosely mounted refractory tube for conducting heated gases from the furnace to the said burning zone, 95 and a damper for each of said openings.

4. In a device of the class described, a 100 tunnel designed to receive a series of movable cars, and to be divided into preheating, burning and cooling zones, a furnace adjacent to one side of said burning zone having a series of openings communicating therewith, to conduct heated gases from the said furnace to the said burning chamber or zone, and a damper for each of said openings. 105

5. In a device of the class described, a 110 tunnel designed to receive a series of movable cars, and to be divided into preheating, burning and cooling zones, a car receiving vestibule at each end of said tunnel, said vestibule being provided with a door at each end designed to be alternately opened and closed so that a car may be moved into or out of the tunnel without unsealing the ends, mechanical means for feeding air under slight pressure to the cooling end of said tunnel, mechanical means for producing a slight vacuum at the preheating end, both of said means being capable of producing a constant flow of air under a constant pressure and at a uniform velocity, and an adjacent and independently constructed furnace at each side of said burning zone, the adjacent wall of each having a series of cor- 115

responding openings, each corresponding set of which is provided with a loosely mounted 120 refractory tube for conducting heated gases from the furnace to the said burning zone. 125

refractory tube for conducting heated gases from the furnace to the said burning zone.

6. In a device of the class described, a tunnel designed to receive a series of movable cars, and to be divided into preheating, burning and cooling zones, and a car receiving vestibule at each end of said tunnel, said vestibule being provided with a door at each end designed to be alternately opened and closed so that a car may be moved into or out of the tunnel without unsealing the ends, mechanical means for feeding air under slight pressure to the cooling end of said tunnel, mechanical means for producing a slight vacuum at the preheating end, both of said means being capable of producing a constant flow of air under a constant pressure and at a uniform velocity, and an adjacent and independently constructed furnace at each side of said burning zone, the adjacent wall of each having a series of corresponding openings, each corresponding set of which is provided with a loosely mounted refractory tube for conducting heated gases from the furnace to the said burning zone.

7. In a device of the class described, a tunnel designed to receive a series of movable cars, and to be divided into pre-heating, burning and cooling zones, a car receiving vestibule at each end of said tunnel, mechanical means for feeding air under slight pressure to the cooling end of said tunnel, and mechanical means for simultaneously producing a slight vacuum at the pre-heating end, both of said means being capable of producing a constant flow of air under a constant pressure and at a uniform velocity.

8. In a device of the class described, a tunnel designed to receive a series of movable cars, and to be divided into pre-heating, burning and cooling zones, and a car receiving vestibule at each end of said tunnel, said cooling zone being provided with a percolator housing over said cars, mechanical means for feeding air under slight pressure to the outside of said percolator housing, and mechanical means for producing a slight vacuum at the under side of said percolator housing.

9. In a device of the class described, a tunnel designed to receive a series of movable cars, and to be divided into preheating, burning and cooling zones, a car receiving vestibule at each end of said tunnel, said cooling zone being provided with a percolator housing over said cars, mechanical means for feeding air under slight pressure to the outside of said percolator housing, mechanical means for producing a slight vacuum at the under side of said percolator housing, and means for regulating the flow of air at the various points within the said housing.
- 10 125
- 15 130

10. In a device of the class described, a

tunnel designed to receive a series of movable cars, and to be divided into preheating, burning and cooling zones, a car receiving vestibule at each end of said tunnel, said cooling zone being provided with a percolator housing over said cars, mechanical means for feeding air under slight pressure to the outside of said percolator housing, mechanical means for producing a slight vacuum at the under side of said percolator housing, and an adjacent and independently constructed furnace at each side of said burning zone, the adjacent wall of each having a series of corresponding openings, each corresponding set of which is provided with a loosely mounted refractory tube for conducting heated gases from the furnace to the said burning zone.

11. In a device of the class described, a tunnel designed to receive a series of movable cars, and to be divided into preheating, burning and cooling zones, a car receiving vestibule at each end of said tunnel, said cooling zone being provided with a percolator housing over said cars, mechanical means for feeding air under slight pressure to the outside of said percolator housing, mechanical means for producing a slight vacuum at the under side of said percolator housing, means for regulating the flow of air at the various points within the said housing, and an adjacent and independently constructed furnace at each side of said burning zone, the adjacent wall of each having a series of corresponding openings, each corresponding set of which is provided with a loosely mounted refractory tube for conducting heated gases from the furnace to the said burning zone.

12. In a device of the class described, a tunnel designed to receive a series of movable cars, and to be divided into pre-heating, burning and cooling zones, said cooling zone being provided with a percolator housing over said cars, mechanical means for feeding air under slight pressure to the outside of said percolator housing, and mechanical means for producing a slight vacuum at the under side of said percolator housing.

13. In a device of the class described, a tunnel designed to receive a series of movable cars, and to be divided into preheating, burning and cooling zones, said cooling zone being provided with a percolator housing over said cars, mechanical means for feeding air under slight pressure to the outside of said percolator housing, and mechanical means for producing a slight vacuum at the under side of said percolator housing, means for producing a series of successive high temperature zones outside of said housing.

14. The combination of a tunnel kiln having a series of transversely arranged inlet and outlet air passages, and a series of kiln cars each of which is provided with a floor comprising a series of fire proof, adjacent, and transversely arranged conductor mem-

bers, each of which has in its upper side, a number of openings in communication with the conductors of said members, said series of passages being in a horizontal line with the said conductors, independent means for controlling the flow of air through each of said passages, mechanical means for feeding air under a slight pressure to a number of said passages and mechanical means, for producing a slight vacuum in the remainder of said passages, both of said means being capable of producing constant flow of air under a constant pressure, and at a uniform velocity.

15. In a device of the class described, a tunnel designed to receive a series of movable ears and to be divided into preheating, burning and cooling zones, and an adjacent and independently constructed furnace at one side of said burning zone, the adjacent walls of said furnace and said kiln having corresponding openings to permit the products of combustion from said furnace to enter said kiln, said furnace being so constructed that it will expand and contract independently of said tunnel. 20 25
